(57) **CLAIM**

The ornamental design for a car headlight, as shown and described.

DESCRIPTION

FIG. 1 is a first perspective view of a car headlight showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 2.

The broken lines shown in the drawings depict portions of the car headlight that form no part of the claimed design. The dash-dot-dash broken line defines the boundary of the enlarged view and form no part of the claimed design.
